UNITED STATES PATENT OFFICE.

ALICE A. ROBERTS, OF NEW YORK, N. Y.

WAIST-LINE GARMENT-SUPPORTER.

1,152,121.

Specification of Letters Patent. Patented Aug. 31, 1915.

Application filed November 4, 1911. Serial No. 658,482.

To all whom it may concern:

Be it known that I, ALICE A. ROBERTS, a citizen of the United States, and resident of the borough of Brooklyn, county of Kings, 5 city and State of New York, have invented certain new and useful Improvements in Waist-Line Garment-Supporters, of which the following is a specification.

This device is intended as a simple, cheap 10 and easily operable means for holding down a shirt waist and supporting a skirt.

In producing my device I have labored to make it as simple as possible without sacrificing strength, or efficiency, and to this 15 end I have provided but two principal parts, one a flexible member and the other a metallic fastener to be used as a securing means therefor. The construction of these separate parts and their operation as well as 20 other new and novel features will appear as the specification progresses.

The following is what I consider the best means of carrying out this invention.

The accompanying drawings form a part 25 of this specification, in which:

Figure 1 is in elevation, partly in perspective, it shows the completed device in operation. Fig. 2 is a view in elevation of certain parts of the device.

30 Similar reference numerals indicate like parts in all the figures where they appear.

The member 1, which should be of a length sufficient to pass around the waist of any person who would be apt to wear 35 the device, must be flexible and I may use a piece of unusually strong ribbon, but I prefer to use a flattened tubular tape not unlike a corset or shoe lacing.

The metallic fastening member 2, I have 40 made of flat brass, though it may be of steel. Should steel be used it should be carefully nickelized so as to guard against rust.

The flat metallic member 2 is provided 45 with a central circular perforation 3, of a diameter equal to the width of the tape 1 or approximately so, a square perforation 4, near one end, and an inwardly projecting slot 5 near the other end, which assist in 50 forming the head or hook 6. The outline of this metallic member may be somewhat different than that shown, but I prefer that it shall be artistically curved and that it shall have all corners rounded.

55 I pass one end of the flexible member 2 through the square perforation 4, and fold

this end of the flexible member back upon the body of the member for a short distance, securing it there by a metallic clamp or staple 7. The free end of the flexible member is then passed around the body at the waist line, and over the shirt waist. This free end is then passed outward through the circular perforation 3, and pulled until the desirable tightness is obtained. A downward movement of the hand causes the free end of the flexible member, or a part thereof to pass into the slot 5 and behind the head 6, and the device is secured.

Care should be taken that the free end or portion be forced downward to a sufficient extent to cause it to be frictionally and securely retained between the back face of the member 2 and the adjacent section of the taut or securing portion of the member 1, 75 in this manner the free end is reliably secured. When so secured it will be noted that the perforation 3 so retains that portion of the flexible member which passes therethrough that any upward movement of 80 that portion of the flexible member which passes through the slot 5, which would tend to loosen the flexible member in the slot is prevented.

To loosen the device it is only necessary 85 to lift the free end of the flexible member until it is disengaged from the slot 5.

A means may be provided for supporting the skirt and such a means may be a safety pin shown arranged upon the back portion 90 or at about mid-length of the flexible member 2. The pin portion of which may be passed through an adjacent portion of a skirt in an obvious manner.

Modifications may be made within the 95 scope of the appended claim without departing from the principle or sacrificing the advantages of this invention.

Having carefully and fully described my 100 invention what I claim and desire to secure by Letters Patent is:—

A garment fastener comprising a rigid member with a plurality of perforations and a slot adjacent to but beyond said perforations, said slot extending transversely 105 downward from the upper edge thereof, a flexible member having one end secured in one of the perforations of said rigid member and the other end adapted to be passed into and through another perforation of a 110 diameter approximately equal to the width of said flexible member, the free end of said

flexible member being adapted to be engaged by a transverse movement into said slot and to be bound between said rigid member and an adjacent section of the securing portion of said flexible member for the purpose set forth.

Signed at New York city, in the county

of New York, and State of New York, this 24th day of October, 1911, in the presence of two witnesses.

ALICE A. ROBERTS.
